UNITED STATES PATENT OFFICE.

JOSEPH LOSEKY, OF CLEVELAND, OHIO.

SAFE.

1,390,571.

Specification of Letters Patent. Patented Sept. 13, 1921.

Application filed August 6, 1920. Serial No. 401,640.

To all whom it may concern:

Be it known that I, JOSEPH LOSEKY, a citizen of the United States, residing at Cleveland, in the county of Cuyahoga and State of Ohio, have invented certain new and useful Improvements in Safes, of which the following is a specification.

This invention relates to an improvement in safes, and the primary object is to provide a safe in which a deposit receptacle is arranged to be rotated to a predetermined position to cover and uncover the door to the receptacle. A further object is embodied in the means for elevating and lowering the deposit receptacle within the walls or main body of the safe so that the receptacle may be rotated and also snugly seated and confined.

In the drawings accompanying this application, Figures 1, 2, 3 and 4 are perspective views, on a reduced scale showing various positions assumed by the rotatable receptacle forming part of the safe. Fig. 5 is a vertical section of the safe on line 5—5, Fig. 9. Figs. 6 and 7 are horizontal cross sections on lines 6—6, and 7—7, respectively of Fig. 5. Fig. 8 is a central vertical section in a plane at right angles to the plane of Fig. 5, showing the deposit receptacle partly turned and Fig. 9 is a similar view showing the receptacle turned to permit the door to be opened, as also shown in Fig. 3.

The safe comprises a base plate 2 having an upwardly extending cylinder 3 forming part thereof or affixed thereto. The main walls or body 4 of the safe is rectangular and has a closed chamber 5 within its lower portion and its upper portion is open or divided to confine a square or rectangular deposit box or receptacle 6 for sliding and rotatable movement therein. Thus, two of the side walls 7 are extended upwardly and provided with spaced ribs 8 upon their inner sides to guide and confine the vertical arm 9 of a yoke which is affixed to or forms part of a piston or plunger 10 operating in cylinder 3. The deposit receptacle 6 has trunnions 11 rotatably supported within ball bearings 12 at the upper ends of arms 9, and when piston 10 and its yoke are at the limit of their down travel and the head of the plunger seated upon the upper end of cylinder 3 the receptacle 6 is fully seated within the upper end of the safe body with its exposed faces flush with the outer surfaces of the

main body 4, and the joints are all closed and fit snugly as appears in Fig. 1. Obviously with the parts in this position it is impossible to rotate receptacle 6; furthermore, when said receptacle has its door 14 or the side which contains said door 14 facing chamber 5 it is impossible to effect entrance into receptacle 6. To do so, plunger 10 and the parts carried thereby must first be elevated, and secondly, the receptacle 6 must be rotated to place the door 14 where it will be exposed and within reach to be opened. The means for raising the plunger 10 comprises a piston 15 which is adapted to reciprocate within the hollow plunger 10 to force oil or any other suitable liquid contained beneath the piston 15 into the working space 16 beneath the lower end of plunger 10. The transfer of the oil is effected through an opening 17 in the bottom plate or head 18 of plunger 10 and a spring or flap valve 19 prevents the return flow of the oil from space 16 into the lower end of the plunger, except when piston 15 is purposely carried downwardly to a point where a pin 20 will pass through opening 17 and engage and open valve 19. When this happens and the plunger is in a raised position, the space 16 is filled with oil which then is expelled through opening 17 by the weight of the parts carried by plunger 10, assuming of course that the piston 15 is free and not checked or prevented from rising upwardly within the plunger under the pressure of the oil transferred. The operating mechanism for piston 15 comprises a link 21 yoked to the piston rod and rotatably connected with an eccentric 22 which is fixed to the inner end of the operating shaft or crank arm 23 having a telescopic handle 24 which is adapted to be withdrawn through a slot or opening 25 in one wall of main body 4 where it may be engaged by the hand of the operator whenever a raising or lowering movement of receptacle 6 is required, and which is only necessary for an interval to turn the receptacle from one position to another. A hinged door 26 with a suitable lock is provided for opening 25 to prevent the operation of the lever 23, and obviously to close the door it is necessary to slide the telescopic handle into chamber 5.

I also mount a bell 27 within chamber 5 and the hammer 28 of this bell is adapted to be actuated by a trip 29 and a wire or cord 110

30 which connects with shaft 23, whenever lever 24 is pressed downwardly. The door 14 and receptacle 6 are preferably provided with a suitable lock 31; either combination 5 or key, or both.

To make the receptacle 6 fire-proof I may also provide it with fire-proof material 32, and to make the working parts accessible I may construct the main body 4 and the base 10 plate 2 in separate pieces and bolt them together from the inside substantially as shown.

What I claim is:

1. A safe comprising a main body having 15 a receptacle tiltable about a horizontal axis, means for vertically shifting said receptacle in different positions therein, said receptacle having a door, said door being covered or uncovered upon shifting and tilting said 20 receptacle.
2. A safe comprising a main body having a receptacle mounted to slide within its upper end and means adapted to raise and lower said receptacle, said receptacle being 25 tiltable about a horizontal axis.
3. A safe having a cylinder therein, a plunger within said cylinder, a piston with-

in said plunger, means adapted to operate said piston, and a deposit receptacle slidably carried by said plunger and mounted to 30 tilt about a horizontal axis within the walls of said safe.

4. A safe, comprising a base having an upright cylinder, a plunger within said cylinder having a yoke, a piston within said plunger having operating connections, a hollow body mounted upon said base confining said parts thereon and a deposit receptacle slidably mounted within said hollow body, said receptacle having a door and said receptacle being rotatably mounted upon said yoke within said body.

5. A safe comprising rectangular walls, two of said walls having upward extensions, a deposit box, a yoke slidably and rotatably supporting said box between said extensions, a power device for raising and lowering said box between said extensions, said yoke connected to said power device.

Signed at Cleveland, in the county of 50 Cuyahoga, and State of Ohio, this 31st day of July, 1920.

JOSEPH LOSEKY.
